(57) **CLAIM**

The ornamental design for a paint brush with integrated hanger, as shown and described.

DESCRIPTION

FIG. 1 is a top right front perspective view of a paint brush with integrated hanger, with the hanger shown in a retracted position;

FIG. 2 is a bottom, right, front perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and

FIG. 8 is a right side elevation view thereof.

FIG. 9 is a top right front perspective view of FIG. 1, with the hanger shown in an extended position;

FIG. 10 is a bottom, right, front perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side elevation view thereof; and,

FIG. 16 is a right side elevation view thereof.

The broken lines immediately adjacent to the shaded areas depict the bounds of the claimed design, while all other
